UNITED STATES PATENT OFFICE

GUSTAVE O. DEGENER, OF SAN FRANCISCO, CALIFORNIA, ASSIGNOR TO ROYAL TYPEWRITER COMPANY, INC., OF NEW YORK, N. Y., A CORPORATION OF NEW YORK

ADDING ATTACHMENT FOR TYPEWRITING MACHINES

Original application filed June 10, 1926, Serial No. 114,950. Divided and this application filed May 25, 1927. Serial No. 194,132.

This application is a division of my prior Patent 1,688,805, Oct. 23, 1928.

The object of the invention herein disclosed is to provide a means whereby all of the keys which operate the adding mechanism are locked unless the totalizer is in proper position to receive the impulse from the master wheel or other transmitting mechanism. The construction shown also acts as a decimal lock to prevent writing of numbers in the spaces usually employed for writing commas and periods in a number.

The invention is embodied in a machine of the same general character as that shown in my prior Patent 1,633,242, June 21, 1927, and there is illustrated herein only so much of the mechanism as is necessary to show the construction and operation of the present invention.

20 In the drawings:

Figure 1 is a vertical longitudinal section through the attachment with parts in elevation.

Figure 2 is a fragmentary view showing a part of the means for locking the keys unless the totalizer is correctly positioned.

Figure 3 is a perspective view of a portion of this means.

Figure 4 is a side elevation of a rocking frame forming a part of the locking means.

Figure 5 is a front view of the frame shown in Figure 4.

Figure 6 is a perspective view of another rocking frame forming a part of the locking means.

The attachment comprises a frame having side members, one of which is indicated at 2, and transverse connecting members 5 and 8 as well as transverse rods 10 and 11 upon which travels the totalizer 12. The numeral key levers H of the typewriting machine are connected by links 15 through crank arms 14 which are carried by the ends of rock shafts 13. An upwardly extending crank arm 16 is attached to the other end of each rock shaft and this crank arm is pivoted at its upper end to a sliding bar 17, the rear end of which is supported and guided by a member 18.

A plurality of cam gears 21 are supported upon a shaft 22 and each gear is provided

with teeth 23 throughout a portion of its periphery with which mesh rack teeth 24 on the sliding member 17. It is obvious that a depression of any key lever will move rearwardly the corresponding sliding bar 17 and operate the cam gear 21 which through mechanism described in my prior application or through other equivalent devices will set up the proper number in the totalizer. The precise character of the connections is immaterial so far as the present invention is concerned.

A universal frame 44 is carried by arms 45 which are mounted on a rock shaft 47 supported by the side bars of the frame of the attachment. The rear ends of the sliding bars 17 engage this universal frame 44 so that it will be rocked each time a numeral key is depressed. A spring 48 is attached at one end to one of the arms 45 and at the other end to a fixed portion of the frame 49 and tends to return the frame 44 to normal position and thereby return the actuated key lever to its normal position.

The universal frame 44 carries a roller 50 which is positioned to engage the cam end 51 of a rocking member 52. This member has a broad bearing on a pivot shaft 53 and has an upper end 54 provided with an offset 55.

This offset 55 rests against the free end of a wire spring 56, the other end of which is attached by a screw 57 to a second rocking frame particularly shown in Figure 6 which is mounted on the same pivot shaft 53. This frame 58 has two side members 59 and 60. The member 59 has an upwardly extending arm 61 with a rounded end which engages between the two portions of a stop member 62 in the form of an open-ended loop to thereby limit the movements of the frame 58 in either direction.

The side 60 of the frame 58 has an upwardly extending arm 63 which is connected by a link 63' to a slide member 64 which is mounted to slide in grooves on a support 65 which is carried by a bracket 66 depending from the cross bar 5. A pawl 67 is pivoted on a short stud 68 carried by the slide 64 and is normally held in central position by two members 69, one of which is shown detached in Figure 3, 100

which members are pivoted on a common pivot 70 and normally drawn toward each other by a coil spring 71, the ends of which engage in notches 72 in the member 69. The 5 rounded ends of these members engage on opposite sides of the pawl 67 and normally hold it in central position although allowing it to move from one side or the other against the tension of the spring 71.

10 A bracket 73 on the totalizer 12 carries a rack member 74 which is provided with teeth 75. These teeth are arranged a proper distance apart for the numerals and are separated by wider spaces wherever a comma or 15 a period would naturally come in the writing of a number.

When a key is actuated the universal frame 44 is operated from the corresponding sliding bar 17 and this results in rocking the 20 frame 52 and through the spring 56 also rocks the frame 58. The rocking of the frame 58 through the arm 63 and link 63' moves the slide 64 with the pawl 67 toward the rack bar 74 and the teeth 75 thereof. If the 25 totalizer carriage is in the proper position for the setting up of the number corresponding to the actuated key, the pawl 67 will directly engage with one of the teeth 75 and thereby the further movement of the slide 64 and the 30 arm 63 of the rocking frame 58 will be prevented. Since the rocking frame cannot move any farther the frame 52 will continue to move and the spring 56 will be tensioned during such movement. The number 35 will therefore be printed and set up in the totalizer in the usual manner. However, if the pawl 67 passes into one of the spaces between the teeth 75, which means that the totalizer is not in proper position or that it 40 is in such position that a comma or period should be written, the movement of the frame 58 will not be stopped but will continue and this will swing the arm 76 downward into the path of the universal frame 44 and stop the 45 movement thereof before the frame has moved far enough to set up the number in the totalizer or to print from the typewriter key.

It is sometimes desired to write in the computing zone without setting up numbers in the totalizer and there is accordingly provided a non-add key 77 which is pivoted at 78 and normally drawn in one direction by spring 79. The rear end of this key is provided with an offset 80 extending to one side thereof. Whenever this key is depressed this offset is moved up sufficiently to be in the path of an arm 81 carried by the rocking frame 58. Therefore, operation of this rocking frame 55 will be prevented by the engagement of the arm 81 with the offset end 80 of the non-add lever, regardless of the relative position of the register.

As stated above, this invention may be employed with widely differing types of com-

puting devices and it is not essential that the same be associated with a typewriting machine. Minor modifications in the precise form and construction can be made without departing from the spirit of the invention 70 which is to be regarded as limited only by the scope of the appended claims.

I claim as my invention:

1. A computing mechanism comprising a travelling totalizer, devices for entering numbers in said totalizer when it is in the computing zone, keys for actuating said devices upon full depression of any key, and means set by the keys for preventing the full depression of said keys to enter a number 75 when the totalizer is not correctly positioned.

2. A computing mechanism comprising a travelling totalizer, devices for entering numbers in said totalizer when it is in the computing zone, keys for actuating said devices, and means set by the keys for preventing the full depression of said keys to enter a number 80 when the totalizer is not correctly positioned, said means comprising a universal frame operated by the depression of any key and a stop movable into position to limit the operating movement of the frame 85 and to thereby prevent full depression of the key.

3. A computing mechanism comprising a 95 travelling totalizer, devices for entering numbers in said totalizer when it is in the computing zone, keys for actuating said devices, and means for preventing the depression of said keys to enter a number unless the totalizer is correctly positioned, said means comprising a rack movable with the totalizer and having a tooth for each position in which a digit should be written, a pawl cooperating with said teeth, and movable between the teeth of the rack upon depression of any key when the totalizer is incorrectly positioned, and a stop movable by a key into a position to limit the effective depression of said key when the pawl is not in 100 register with a tooth of the rack.

4. A computing mechanism comprising a 115 travelling totalizer, devices for entering numbers in said totalizer when it is in the computing zone, keys for actuating said devices, and means for preventing the depression of said keys to enter a number unless the totalizer is correctly positioned, said means comprising a universal frame operated by the depression of any key, a second frame yieldingly moved 120 by the first frame and carrying a stop which is moved into position to stop the universal frame unless the totalizer is correctly positioned.

5. A computing mechanism comprising a 125 travelling totalizer, devices for entering numbers in said totalizer when it is in the computing zone, keys for actuating said devices and decimal lock mechanism for preventing the depression of said keys to enter a num- 130

ber unless the totalizer is correctly positioned, said mechanism comprising a toothed member travelling with the totalizer, a pawl moved to cooperate with the toothed member by the initial depression of said keys, and means for preventing a further depression of the keys unless the pawl engages one of said teeth.

6. A computing mechanism comprising a travelling totalizer, devices for entering numbers in said totalizer when it is in the computing zone, keys for actuating said devices, and decimal lock mechanism for preventing the depression of said keys to enter a number unless the totalizer is correctly positioned, said mechanism comprising a toothed member travelling with the totalizer, a pawl moved to cooperate with the toothed member by the initial depression of said keys, a universal frame operated by said keys, and means for stopping the movement of said frame unless the pawl engages one of said teeth.

7. A computing mechanism comprising a travelling totalizer, devices for entering numbers in said totalizer when it is in the computing zone, keys for actuating said devices, and decimal lock mechanism for preventing the depression of said keys to enter a number unless the totalizer is correctly positioned, said mechanism comprising a toothed travelling with the totalizer, a pawl moved to cooperate with the toothed member by the initial depression of said keys, a universal frame operated by said keys, a second frame yieldingly moved by the first frame, and a stop carried by the second frame and moved into the path of the universal frame unless the pawl engages one of said teeth.

8. A computing mechanism comprising a travelling totalizer, devices for entering numbers in said totalizer when it is in the computing zone, keys for actuating said devices, said totalizer being free to move at all times when in the computing zone, means including a rocking frame which operates automatically to prevent effective depression of said keys unless the totalizer is correctly positioned, and a separate key cooperating with the rocking frame for disabling the last mentioned means.

9. In decimal lock mechanism for computing mechanism having a travelling totalizer and key actuated devices for entering numbers therein, the combination of a toothed device carried by the totalizer, a slide operated by the initial depression of the keys, a pawl pivoted on said slide and moved toward said teeth, and means for preventing further depression of said keys unless the pawl engages a tooth.

10. In decimal lock mechanism for computing mechanism having a travelling totalizer and key actuated devices for entering

numbers therein, the combination of a toothed device carried by the totalizer, a slide operated by the initial depression of the keys, a pawl pivoted on said slide and moved toward said teeth, resilient means for holding said pawl normally in central position, and means for preventing further depression of said keys unless the pawl engages a tooth.

11. In decimal lock mechanism for computing mechanism having a travelling totalizer and key actuated devices for entering numbers therein, the combination of a device carried by the totalizer and having a tooth for each position wherein a number should be entered, a pawl moved toward said teeth by the initial depression of any key, and means for preventing further depression of said key to enter a number in the totalizer unless the pawl engages a tooth.

12. A computing mechanism comprising a travelling totalizer, devices for entering numbers in said totalizer when it is in the computing zone, keys for actuating said devices and means operated by an initial depression of any key for preventing sufficient depression to enter a number in the totalizer unless the totalizer is correctly positioned.

13. In a computing machine, the combination of a traveling totalizer, devices for entering numbers in the totalizer when the same is in the computing zone, keys for actuating said devices upon full depression of any key, means set by the keys for preventing full depression thereof to enter a number when the totalizer is not in correct position, and means controlled by the totalizer for determining whether the preventing means shall or shall not function.

14. In a computing machine the combination of a traveling totalizer, devices for entering numbers in the totalizer when in the computing zone, keys for actuating said devices upon full depression of any key, means set by the keys for preventing full depression thereof to enter a number when the totalizer is not in correct position, a rack carried by the totalizer, and a pawl cooperating with the rack and controlling the operation of the preventing means.

15. In a computing machine the combination of a traveling totalizer, keys for effecting the entry of amounts therein upon full depression of any key, means for preventing the full depression of the keys when the totalizer is not correctly positioned, a universal member adapted to be operated by any of the keys, a stop adapted to be placed in the path of the universal member, and means controlled by the totalizer for moving the stop into the path of the member when the totalizer is not in correct position.

In testimony whereof, I have hereunto subscribed my name.
